UNITED STATES PATENT OFFICE.

ANSEL H. PHINNEY, OF TURNER, MICHIGAN.

ORE SIZER AND CONCENTRATOR.

SPECIFICATION forming part of Letters Patent No. 763,019, dated June 21, 1904.

Application filed August 31, 1903. Serial No. 171,416. (No model.)

To all whom it may concern:

Be it known that I, ANSEL H. PHINNEY, a citizen of the United States, residing at Turner, in the county of Arenac and State of Michigan, have invented certain new and useful Improvements in Ore Sizers and Concentrators; and I do declare the following to be a full, clear, and exact description of the invention, such as will enable others skilled in the art to 10 which it appertains to make and use the same.

My invention is an improved ore sizer and concentrator especially adapted for use for wet crushed ores, but also adapted for use for "floating" or collecting the solids from aqueous mixtures, as in the manufacture of paris white and other materials.

My invention consists in the peculiar construction and arrangement of devices herein-after described and claimed.

20 In the accompanying drawings, Figure 1 is a vertical longitudinal sectional view of an ore sizer and concentrator embodying my improvements. Fig. 2 is a top plan view of the same. Fig. 3 is a transverse sectional view 25 of the same, taken on the plane indicated by the line *a a* of Fig. 1.

In the embodiment of my invention I provide a vat or trough 1, of suitable size, which in practice is usually about twenty feet long, 30 four feet wide, and ten inches deep. The bottom of the vat or trough is formed by a plurality of hoppers 2, which extend from end to end thereof, and the sides of which converge downwardly. Each of said hoppers is 35 provided at its lower end with a discharge-opening 3, controlled by a suitable valve or gate 4. The trough or vat is provided also with a false bottom 5, which extends from end to end and side to side thereof, the said 40 false bottom being formed of a number of longitudinally-disposed bars 6, which are triangular in form and suitably spaced apart, as at 7, to admit of the passage of ores and other finely-ground material between them. The 45 sides of the said bars 6 converge upwardly, as shown. The trough or vat is supplied at one end with material at the surface of the liquid by a pipe or other suitable duct 8 and is provided at its opposite end at the level of

the top of the liquid with a discharge spout 50 or lip 9.

In the operation of my invention the material, together with water, is fed to the trough or vat by a supply-duct 8. The screen formed by the false bottom arrests the descent of the 55 larger particles of quartz and other material. The rate of deposit from the liquid will be controlled by the factors of the size of the particles and also their specific gravity, the larger particles of quartz settling with smaller 60 ones of the much heavier ores. The larger particles of rock may be afterward separated from the deposits in the different hoppers by screening and reground, if desired. The material which becomes deposited in the va- 65 rious hoppers may be drawn therefrom from time to time or continuously, according to the conditions of the case, by means of the valves or gates 4. It will be understood that the material is thoroughly washed as it passes 70 through the trough or vat and that the lighter worthless particles are carried off by the water from the trough or vat, while the valuable ores or other heavier particles by specific grav- 75 ity become precipitated in the hoppers. The 75 triangular bars which form the coarse bot- 80 tom or screen by the provision of their up-wardly-converging sides facilitate the pas- 85 sage of the finer particles through said screen. The said bars, in effect, constitute corruga- 90 tions which are longitudinally disposed in the screen, and the spaces between the bars, in ef- 95 fect, constitute openings in the screen. The said screen cuts off the moving liquid in the vat from the still liquid in the hoppers and the corrugations 10 to prevent counter-currents, it being desirable that the solution should move at an even rate of speed from the inlet to the outlet of the vat. Such a motion is facilitated by the bars of the screen, and a finer deposit is received in each suc- 95

From the foregoing description, taken in connection with the accompanying drawings, the construction and operation of the inven-

tion will be readily understood without requiring a more extended explanation.

Various changes in the form, proportion, and the minor details of construction may be resorted to without departing from the principle or sacrificing any of the advantages of this invention.

Having thus fully described my invention, what I claim as new, and desire to secure by Letters Patent, is—

1. An ore sizer and concentrator comprising a vat having a discharge element at one end, means at the opposite end to supply material, suspended in liquid, to the vat, a plurality of hoppers below the level of the discharge element and forming a series of water-chambers, and a screen forming a false bottom extending over the hoppers, and having longitudinally-disposed laterally-spaced screen elements extending below the water-level of the vat, said screen elements serving to form a series of straight guiding-channels opening at the bottom into the hoppers and extending

from the feed to the discharge ends of the device.

2. An ore sizer and concentrator comprising a vat having a discharge element at one end, a plurality of hoppers below the level of the discharge element and forming a series of water-chambers, and a screen forming a false bottom extending over the hoppers and extending below the water-level of the vat, said screen being provided with longitudinally-disposed bars spaced apart and having upwardly-converging inclined sides, said bars forming a series of straight guiding-channels opening at the bottom into the hoppers and extending from the feed to the discharge ends of the device.

In testimony whereof I have hereunto set my hand in presence of two subscribing witnesses.

ANSEL H. PHINNEY.
